UNITED STATES PATENT OFFICE.

FRANCIS V. TREMBLAY, OF RUMFORD, MAINE.

SHOE-FASTENER.

1,155,973.

Specification of Letters Patent.

Patented Oct. 5, 1915.

Application filed June 17, 1914. Serial No. 845,661.

To all whom it may concern:

Be it known that I, FRANCIS V. TREMBLAY, a citizen of the United States, residing at Rumford, in the county of Oxford and State of Maine, have invented certain new and useful Improvements in Shoe-Fasteners; and I do hereby declare the following to be a full, clear, and exact description of the invention, such as will enable others skilled 10 in the art to which it appertains to make and use the same.

This invention relates to shoe fasteners, and one of the principal objects of the invention is to provide a shoe fastening of 15 simple construction which will operate smoothly, which will be quick and simple in operation and use, which will eliminate the use of buttons and laces, and will close the shoe about the foot yieldingly.

20 Another object of the invention is to provide a shoe fastener having a sliding tongue provided with a series of ball members, and the shoe upper at the opposite sides of the ankle or instep opening is provided with 25 slotted tubes in which said balls are adapted to be slidably connected to hold the shoe firmly on the foot, the tongue of the shoe being preferably elastic.

The foregoing and other objects may be 30 attained by means of the construction illustrated in the accompanying drawing, in which,

Figure 1 is a perspective view of a shoe provided with a fastener made in accordance 35 with this invention, Fig. 2 is a plan view of the resilient tongue shown broken away at the central portion, Fig. 3 is a perspective view of the ball and tube members of the fastener, and Fig. 4 is a sectional view 40 through the front part of the upper of the shoe and showing the fastener in operative position.

Referring to the drawing, the numeral 1 designates the upper of a shoe having an 45 ordinary instep and ankle opening, and 2 is a tongue formed preferably of elastic webbing secured at its lower end underneath the vamp of the shoe. The tongue 2 is provided with ball members, each comprising a shank 3 having points or prongs 4 stamped therefrom to be used as means for fastening the

ball members to the tongue, although the shank may be formed with openings for stitches if desired.

Formed on the shank 3 is a ball member 55 which may be either solid or hollow as desired. As shown, the ball members are secured in pairs to the tongue 2 with the shank portions arranged inwardly and the ball members outwardly as clearly shown in 60 Fig. 2.

The slotted tubular members comprise each a shank 6 having prongs or openings 7 formed therein for securing the shank to the opposite edges of the instep or ankle opening, and connected to the shank 6 is a tube 65 of any desired length 8 provided with a slot 9 of a width to receive the shank 3 of the ball member.

The manner of using the fastener may be 70 described as follows: The lower ball members 5 may be slightly larger than the others and when the first two or three members are connected to their respective tubes 8 upon opposite sides of the opening, the tongue 2 75 may be pulled upward and all the ball members will engage their respective tubular members 8. To prevent the tongue from slipping downward, a ball and socket snap fastener 10 and 10^a may be connected to the 80 upper portion of the tongue and when the tab 11 is bent over the upper edge of the upper and secured by the ball and socket fastener, the tongue 2 cannot slip downward.

85 From the foregoing it will be obvious that a shoe fastener made in accordance with this invention is simple in construction, may be manufactured at comparatively low cost, will operate smoothly and quickly, and will 90 hold the shoe on the foot in an elastic and resilient manner and will fit snugly around the ankle and instep of the wearer.

Slight changes may be made in the details of construction without departing from the 95 spirit and scope of the invention is defined in the claim.

What is claimed is:—

A shoe fastener comprising an elastic tongue, having oppositely disposed ball 100 members connected at spaced intervals thereto, slotted tubular members connected

at spaced intervals to the meeting edges of the upper for engagement with said ball members, said tongue having an extending upper end forming a flap, and having fastening members on the flap and end of the tongue, so the flap may be turned down over the uppermost pairs of ball members to hold the tongue from sliding movement and the

ball and slotted tubular members from disconnection.

In testimony whereof I affix my signature in presence of two witnesses.

FRANCIS V. TREMBLAY.
